SHOE MACHINES

James P. Carter, Beverly, Mass., assignor to United Shoe Machinery Corporation, Flemington, N.J., a corporation of New Jersey

Application January 7, 1957, Serial No. 632,865

10 Claims. (Cl. 112—52)

The present invention relates to improvements in machines for attaching welts to lasted shoe uppers and sole members, and more particularly to machines having mechanisms for automatically severing the welt and for positioning the severed end in readiness to start an operation on a new shoe. A machine of the particular type referred to is disclosed in an application for United States Letters Patent, Serial No. 558,933, filed January 13, 1956, in the name of the present inventor.

The machine of the application above referred to is a Goodyear Welt Inseam Sewing Machine equipped with a feeler controlled welt severing mechanism thrown into operation automatically by the leading end of the welt first attached to a sewed heel seat shoe as the seam being inserted nears completion. When a shoe having a welt extending around the forepart only, from heel-breast line to heel-breast line, is being operated upon a feeler is useless for controlling the welt severing operation, particularly for breast-to-breast work, there being nothing to actuate such feeler where the leading end of the welt first attached to the shoe is not carried a second time across the sewing point. Accordingly, it is necessary in the machine of the prior application to make certain adjustments and changes in the control parts, so that the welt may be severed directly under the control of the operator at the proper point as the seam is being completed.

An object of the present invention is to provide a shoe sewing machine with conveniently controlled automatic welt severing mechanism operative alternatively, either upon shoes of the sewed heel seat type or upon shoes having welt attached about the foreparts only. Other objects are to improve the construction and mode of operation of mechanism for causing a welt to be severed automatically and for advancing the severed welt end across the point of operation in any type of shoe sewing or other fastening forming machine before starting a new seam and to provide a simple form of alternative adjustment readily adaptable to all sewing conditions, so that the same machine may operate satisfactorily upon either sewed heel seat or heel-breast to heel-breast work.

In accordance with the purposes outlined above, an important feature of the invention resides in a treadle controlled machine of the type referred to, equipped with the usual stitch-forming, feeding, and guiding devices for shoe parts, automatic welt severing mechanism including a welt severing knife, an electromagnetic solenoid for actuating the knife, a feeler for engaging the leading end of a welt already attached to a sewed heel seat shoe, as that end approaches the stitch-forming devices, an energizing switch actuated by the feeler and a safety switch interposed in circuit with the energizing switch to prevent unintentional operation of the severing mechanism, in which machine there is provided a separate treadle actuated, operator-controlled switch for energizing the solenoid when approaching the end of a sewing operation for a shoe sewn only about its forepart. Preferably, a selector switch is connected in circuit with the treadle

2

actuated switch for rendering the treadle actuated switch effective to energize the solenoid or for rendering the treadle-actuated switch ineffective to energize the solenoid. In one form of this feature the selector switch connects 5 the safety switch in circuit with the solenoid when the treadle actuated switch is ineffective. As hereinafter described, means under the operator's control also is provided for actuating the safety switch in advance of the end of a seam to render one of the energizing switches 10 effective to energize the solenoid, and a latch is provided for retaining the safety switch in circuit connecting position until the solenoid circuit is completed by closing the energizing switch. To prevent the welt from being severed unintentionally after the machine is restarted, in this feature of the invention, means are provided for releasing the safety switch from the latch when the solenoid is energized.

In a further aspect of the invention, which is applicable to machines equipped with both a foot treadle and a knee lever for controlling an operation of sewing welts to lasted shoe uppers and insole members, and more generally to other types of attaching operations, in which a knee lever is latched in actuated position during the operations and while the foot control treadle is depressed, 20 connections are provided between the latch and the treadle for releasing the safety switch from the latch when the treadle is raised to terminate the operations. As hereinafter illustrated, these connections are partly mechanical and partly electrical, the latch being moved to unlatching position by an electromagnet energized through a switch actuated by the welt severing knife solenoid.

These and other features of the invention, as hereinafter described and claimed, will be apparent from the following detailed specification and accompanying drawings, 35 in which

Fig. 1 is a view in front elevation, partly broken away and reduced in height, of a welt shoe sewing machine embodying the features of the present invention;

Fig. 2 is a detail view partly broken away and reduced 40 in height, on a somewhat enlarged scale, looking from the right side of a base of the machine shown in Fig. 1 and illustrating a control treadle and knee lever arrangement employed in the machine, the parts being shown while the machine is in stopped position;

Fig. 3 is a detail view showing the parts of the knee lever connections and a wiring diagram of the machine, 45 with the parts illustrated in running position;

Fig. 4 is a similar view of the knee lever illustrating the positions of the parts when the control treadle is moved to machine stopping position;

Fig. 5 is a detail view partly in section looking from 50 the right side of the machine of a portion of the stopping mechanism;

Fig. 6 is a sectional detail view illustrating the relationship of a needle, awl, and welt severing knife while engaging a feeler and a channel guide together with a shoe being operated upon by the machine;

Fig. 7 is a detail plan view illustrating the manner of 60 operation of the machine on a sewed heel seat shoe; and

Fig. 8 is a similar detail view illustrating the manner 65 of operation of the machine on a conventional Goodyear welt shoe to which a welt is sewn from heel-breast line to heel-breast line.

The machine illustrated in the drawings is a shoe in-seam sewing machine similar to that disclosed in United States Letters Patent No. 1,971,575, granted August 28, 1934, and No. 2,041,945, granted May 26, 1936, both upon application of Alfred R. Morrill, and also similar to that referred to in the present inventor's co-pending application above identified. The machine of the application has the usual stitch-forming, feeding and guiding devices for the parts of a shoe, a welt severing knife

mounted for movement toward and from the welt as it passes through its guiding device, automatic mechanism for actuating the knife including an electromagnet, and a feeler mounted for engagement with the leading end of the welt already attached to a shoe, as that end approaches the stitch-forming device. The machine of the application is primarily intended for operation upon a shoe which has a welt sewn thereto throughout the length of its bottom marginal portions, including the heel seat of the shoe, so that the seam is completed by stitches overlapping the abutting ends of the welt.

As illustrated in Figs. 3 and 6 of the drawings, the parts of a shoe including an insole 6, an upper 8, and a welt 10 are operated upon by the usual stitch-forming and feeding devices and the leading end, indicated at 12, of the welt first attached to the shoe, is engaged by the feeler, indicated at 14, movable toward and from a position of engagement by the welt end 12 during its feeding movement. When the feeler 14 is engaged by the welt end 12, as that end approaches the stitch-forming devices, a welt severing knife 16 is projected against the welt running from a supply, at a position in advance of the sewing point in the machine where there is no danger of contact with parts of the shoe other than the welt by the knife during the sewing operations. The machine thus continues in operation for a sufficient length of time to insert one or more stitches overlapping the ends of the welt which are brought into abutting engagement with each other.

The machine is thereafter brought to rest and the mechanisms are thrown into operation for advancing the end of the welt remaining in the machine across the point of operation of the stitch-forming devices in preparation for starting an operation upon a new shoe.

In order to enable the machine of the prior application to operate upon a conventional Goodyear welt shoe, in which the welt is attached to the insole and upper about the forepart only of the shoe from heel-breast line to heel-breast line, it is necessary to render the welt end feeler inoperative and to make a number of other adjustments which may be difficult and time consuming. Also, after such adjustments are made it is necessary in sewing a Goodyear welt shoe from heel-breast line to heel-breast line only, for the operator to gage accurately the position along the welt at which it is to be severed and, also thereafter, to bring the machine to rest with a short length of the welt remaining unattached to the shoe, so that a welt butting operation may readily be performed without requiring an excessively long length of welt to be severed from the shoe and wasted.

For the purposes of avoiding the necessity for the operator to estimate the proper position for severing the welt in a conventional Goodyear welt shoe with the best results, for bringing the machine to rest with the proper length of welt remaining unattached to the shoe, and for simplifying the adjustments required when transforming the machine from a condition where it is adapted for sewed seat work to a condition where it is adapted for breast-to-breast work, the machine of the present invention is equipped with an improved arrangement of control connections. The improved control connections comprise a member capable of being displaced by the operator of the machine for causing the welt severing knife to be actuated independently of the engagement of the welt on a shoe by the feeler. In the preferred construction alternatively operable means is provided for enabling a simple shift to be made from a condition of automatic control by the feeler to a condition requiring the operator displaceable member to be actuated in severing the welt. The improved connections also include a safety switch similar to that employed in the machine of the prior application when the machine is utilized for sewed seat work.

Referring to Figs. 6 and 7, the action of the machine is illustrated in severing the welt at the end of a sewed

seat inseaming operation. In Fig. 8 a conventional Goodyear welt shoe which has the welt attached from heel-breast line to heel-breast line is illustrated. In sewed heel seat work the welt severing operation is controlled by the engagement of the leading end portion 12 of the welt, first attached to the shoe with the welt end feeler 14 secured by a screw 18 (Fig. 3) to a lever 20 and pressed yieldingly against the leading end already attached to the insole by stitches starting as close as possible to the leading end. As soon as the leading end 12 of the welt engages the feeler 14 the knife 16 severs the welt between the shoe and the supply as the welt passes through its guiding devices, leaving a short unattached length projecting from the shoe a distance equal to that between the last formed stitch and the leading end 12, the knife being arranged to form a beveled cut matching that on the leading end 12.

When the machine is to be transformed to a condition where it is adapted for breast-to-breast work, illustrated in Fig. 8, adjustments are made to cause the first stitch of a seam to be inserted in the welt at some distance from the leading end 12, as shown in Fig. 8, rather than close to the leading end, as in Fig. 7. By so doing, a suitable length of unattached welt is supplied for a later performed welt butting operation to enable the welt at its ends to be fitted smoothly to a heel. Correspondingly, the same length of unattached welt is required at that end finally attached to a shoe, it being unnecessary to insert stitches across the final end, indicated at 22, as in sewed seat work. For this reason it is desirable to delay stopping the machine after severing the welt in sewed seat work. Delayed stopping of the machine causes the seam to continue until several stitches are inserted across the joint between the leading and final ends of the welt.

To attach the parts of the shoe the machine is equipped with the usual chain-stitch forming, work feeding, and guiding devices, including a curved hook needle 24 (see Fig. 6), an awl 26, a channel guide 28, a needle looper 30 (see Fig. 1), a back rest 32, a sewing welt guide 33 and other devices constructed and operating in the same manner as shown in the above-mentioned patents, No. 1,971,575 and No. 2,041,945. The stitch-forming and other devices are actuated by a main sewing cam shaft 34, provided at its left end with a hand wheel 36.

Driving and stopping mechanisms for the sewing shaft also are provided, including a vibrating lever 38 (see Fig. 5), a lock bolt 40 mounted for vertical sliding movement in a horizontally yielding carrier 42, and other manually controlled and automatic connections operated by the sewing shaft 34 for bringing the machine to rest. The driving and stopping mechanisms are controlled in part by the operator and in part by the automatic connections which are thrown into operation to stop the machine with the needle retracted from the work and free of sewing thread. Control of the driving mechanism is exercised by the operator through displacement of a control treadle 44 (Figs. 1 and 2) which is held yieldingly in a raised position by a spring 45, the machine being started by a downward pressure on the treadle and brought to rest at its predetermined stopping position when the treadle is released.

The mechanism for actuating the welt severing knife 16 includes an electromagnetic solenoid 46 (see Figs. 1 and 3) having a central reciprocating armature 48 (Fig. 3) directly connected to the knife. To retract the armature 48 after the solenoid is de-energized, the armature has connected to it the lower end of a spring 50 (Fig. 1) stretched between the armature and a fixed part of the machine. When the solenoid is energized, the armature is drawn downwardly with sufficient rapidity to cause the knife 16 to sever the welt while the machine is running without interfering with the operation of the machine in other respects, so that when the feeler engages the leading end of the welt, it is possible to continue a sewed heel

seat sewing operation without interruption across the joint in the welt.

The feeler 14 is operatively connected to a solenoid energizing switch 52 in a manner more specifically illustrated and described in inventor's prior application, Serial No. 558,933. Briefly, the connections between the feeler 14 and the energizing switch 52 include the lever 20 on which the feeler is mounted, a horizontal link 54 connecting the lever 20 and a downwardly extending arm on a lever 56 provided with a pin 58. The feeler mounting lever 20 is rotatable on a fixed stud 69 upon which a carrier plate 62 also rotates. The carrier plate 62 supports a pin 64 forming a fulcrum for the lever 56. The pin 58 in the lever 56 is so disposed that when the carrier plate 62 is swung about the stud 69 the pin moves into a position in alignment with the actuating button on the energizing switch 52 and at the same time the feeler 14 moves into a position where it will be actuated by the leading end 12 of the welt as that end approaches the point of operation of the stitch forming devices. As soon as the leading end 12 of the welt engages the feeler, it causes the pin 58 to be moved still further and against the button of the energizing switch 52, the electrical circuit through the energizing switch thereby being closed. When the carrier plate 62 is in the position shown in Fig. 3, the feeler 14 can no longer be actuated by the leading end of the welt, the feeler then being in a safe or inoperative position.

To bring the feeler 14 into an active position, connections more fully described in inventor's prior application, between the carrier plate 62 and a knee lever 65 actuated by the operator are thrown into operation. These carrier plate connections include a link 66 pivotally connected at its left end to the carrier plate 62 and at its right end to an arm 68 (see Fig. 1) secured to a shaft 70 having fixed to it a second arm 72 pivotally connected to a cable 74 running downwardly past grooved wheels 76 to a point of connection with a horizontal arm of the operator displaceable member comprising a bell crank 78 (see Fig. 3) fulcrumed on a fixed bracket 80. A vertical arm of the bell crank 78 is connected through a horizontal link 82 to a pin 84 in the knee lever 65 rotatably mounted for limited movement about a fixed pin 86 and provided with a knee pad 88 disposed in a position for convenient engagement with the leg of an operator standing in front of the machine.

As a further means to prevent unintentional operation of the welt severing knife, the operator displaceable bell crank 78 carries a screw 90 which is movable toward and from engagement with a safety switch 92 interposed in circuit with the feeler actuated switch 52. Through the connections thus described, a safety release of the feeler 14 from active position is provided and the electrical circuit, including the feeler actuated energizing switch 52 and the solenoid 48, is normally maintained disconnected from a main power supply line 94 (Fig. 3), the terminals of which are mounted on the machine.

The usual procedure followed when operating upon sewed heel seat shoes is to press the knee pad 88 rearwardly just before the leading end 12 of the welt is observed to approach the point of operation in the stitch-forming devices. Depressing the knee pad moves the feeler 14 and the pin 58 into active positions so that the feeler when engaged by the leading end of the welt may close the switch 52. As soon as the feeler is engaged by the leading end of the welt, the welt is severed and the machine continues in operation until welt attaching stitches are inserted across the joint between the leading and final ends of the welt. Thereupon, the operator raises his foot from the control treadle 44 and the machine is brought to rest. As the machine is brought to rest the welt advancing mechanism, more fully disclosed in inventor's prior application, transports the end of the welt remaining in the machine across the point of operation of the stitch-forming devices to a position where it will

be engaged by the needle as a new sewing operation is started.

To enable the machine of the prior application to operate on conventional Goodyear welt shoes, in which the welt is attached to the insole and upper along the forepart of the shoe from heel-breast line to heel-breast line, the energizing switch 52 is held closed so that the welt severing knife will be actuated merely by closing the safety switch whenever the knee pad 88 is pressed regardless of the position of the feeler 14. For this purpose there is located for selective movement toward and from the feeler controlled energizing switch 52, as in the prior machine, an interponent arm 96 (see Fig. 3) having a cam surface to depress the button of the energizing switch. The interponent arm 96 is moved away from the button of the energizing switch 52 while operating upon sewed seat work. When sewing breast-to-breast shoes the interponent arm 96 is moved to the position of Fig. 3 where it closes the switch 52 and blocks the movement of the pin 58 toward the switch and thus holds the feeler out of engagement with the welt on the shoe.

In sewing conventional Goodyear welt shoes about the forepart from heel-breast line to heel-breast line only, in the machine of the prior application, it is necessary for the operator of that machine to press the knee pad 88 to actuate the safety switch 92, energizing the circuit to the solenoid 46 and at the same time that the knee of the operator's left leg is being utilized for this purpose, his left foot is raised to release the control treadle 44. In so doing it has been found that the operator's knee is subject to injury, the skin being abraded by the releasing movement of the control treadle while pressure is being applied to the knee pad 88. To avoid the danger of injury to the operator's knee and to facilitate control of the machine in other respects, the necessity for holding the knee pad 88 pressed while releasing the foot treadle 44 in operating upon heel-breast line to heel-breast line shoes has been eliminated.

According to the present invention a separate operator controlled energizing switch is provided in place of the feeler actuated switch 52 for connecting the knife actuating solenoid in circuit with the main line 94 when sewing a shoe with welt attached to its forepart only. The operator controlled energizing switch is indicated at 98 (Figs. 1 to 4, inclusive) and is mechanically connected to be actuated upon the release of the operator-controlled treadle 44 rather than upon the movement of the knee pad, the safety switch being held closed mechanically after the knee pad is depressed. However, the knee lever is still employed to control a safety release for the knife actuation. Thus, the welt severing knife is not actuated in case it is necessary to bring the machine to rest before the end of the seam attaching a welt to a shoe is reached. Avoiding actuation of the welt severing knife in this manner is of particular benefit where thread breakage necessitates stopping the machine at an intermediate part of the seam or where repair work on a shoe is being performed.

To avoid the possibility that the operator-controlled switch 98 will cause the welt severing knife to be actuated unintentionally when operating upon sewed seat shoes, the circuit to the switch 98 has interposed in it a selector switch 100, which is of the two-pole double throw type, one of a set of poles being connected by a wire 102 with the operator-controlled switch 98 and one of a set of poles being connected by a wire 104 with the safety switch 92. The safety switch, however, is connected through a lead 106 to the positive side of the line 94. Thus, the selector switch 100 is in circuit with the safety switch for closing the circuit thereto or for connecting the operator-controlled switch 98 directly with the solenoid circuit through a wire 107, running through a conductor 108, passing through a test switch 110 when in its solid line position, the feeler control switch 52, the solenoid 46 and the negative side of the line 94.

To hold the safety switch 92 closed after the knee pad is pressed rearwardly so that it is no longer necessary for the operator of the present machine to subject himself to injury as the foot treadle 44 is released, the lower extremity of the vertical arm in the bell crank 78 forms a pawl engaging a tooth on a latch 112 (see Fig. 2). The latch 112 is rotatably mounted on a pin 114 secured in a downwardly extending bracket 116 on the frame of the machine. The bracket 116 has secured to its lower end an arm 118 on the upper surface of which is mounted a solenoid 120, having an armature 122 movable vertically therein. The armature 122 is connected through a link 124 with the forward end of the latch 112 in such a way that when the solenoid is energized the latch is disengaged from the vertical pawl arm of the bell crank 78. To maintain the latch in engagement with the pawl arm, a spring 126 is stretched between a pin on the latch and a pin on the link 82 just above it. As soon as the latch is released from the pawl arm, the bell crank 78 is released and actuated in a clockwise direction, as viewed in Fig. 2 through the action of a spring 128 connected to a hook on the vertical arm of the bell crank 78 and one end of the pin 86. Release of the pawl arm on the bell crank 78 enables the safety switch 92 to open after the welt has been severed and before the machine is brought to rest, so that the safety switch is returned to safe position ready for the machine to start an operation on a new shoe.

To energize the latch releasing solenoid 120 the armature 48 of the knife actuating solenoid has formed on it a cam enlargement 130 (Fig. 3) acting on a roll 132 on a horizontal arm of a lever 134 whenever the knife actuating solenoid is energized. The lever 134 is fulcrumed on a stud 136 projecting from the machine frame and has an upwardly extending arm, in which is fixed a screw 138. The upper end of the screw 138 cooperates with a spring actuated switch 140, one terminal of which is connected to a conductor 142 running to the latch releasing solenoid 120, and the other terminal of which is connected to a conductor 144 running to the positive side of the line 94. The operation of the safety switch and the energization of the knife actuating solenoid, thus described occur while the selector switch 100 is shifted either to a closing position marked "B—B" between the conductors 102 and 108 or to a closing position marked "S—S" between the conductors 104 and 107.

To actuate the operator controlled energizing switch 98 whenever the foot treadle 44 is released by the operator, the foot treadle is pivotally connected to the lower end of a rod 146, the upper end of which is pivotally connected to a cam arm 148 rotatably mounted on a shaft 149 secured to the operator-actuated knee lever 65. The free end of the cam arm 148 is arranged to engage a roll 150 on a lever 152 rotatably mounted on a pivot 154 (Fig. 3) fixed in an angle plate 156 secured to the bracket 116 (see Fig. 2). A vertical arm of the lever 152 is movable toward and from the operator-controlled energizing switch 98 and when the cam arm engages the roll 150 the energizing switch 98 is closed. Engagement of the cam arm 148 with the roll 150 can occur only when the knee lever 65 is pressed rearwardly and retained in rearwardly pressed position by the latch 112 engaging the pawl arm of the bell crank 78. Thus, the mounting of the cam arm on the shaft 149 carried by the operator actuated knee lever 65 serves in place of a safety switch in preventing actuation of the welt severing knife at all times during operation of the machine, except when a sewing position is reached on a shoe just in advance of a seam end. At this time the operator presses the knee pad 88 rearwardly to bring the cam arm into the range of the cam roll 150, so that the welt knife solenoid 46 may be energized. At all other times the cam arm is held away from the roll 150.

In order to insure that the final stitches of a seam will be inserted overlapping the abutting ends of the welt, so

that a secure attachment of the welt ends to the shoe will be obtained, the driving and stopping mechanism of the illustrated machine is provided with a counting mechanism illustrated in Fig. 5. The lock bolt 40 in the driving and stopping mechanism is connected through a link 158 with one arm of a three-armed lever 160 having a cam surface on one arm engaged by a roller 162 on one end of a shaft 164. The three-armed lever 160 is rotatably mounted on a screw 165 threaded into the machine frame. The shaft 164 has fixed to one end an arm 166, to which the upper end of a driving and stopping control treadle rod 168 is pivotally connected, the lower end of the rod 168 being similarly connected to the treadle 44. At the end of a seam the control treadle 44 is released and in the machine of Patent No. 1,971,575 the lock bolt immediately engages an opening in the vibrating lever 38, causing the sewing shaft 34 to be brought to rest in predetermined stopping position after insertion of a single stitch. In the present machine, however, the lock bolt 40 is delayed in its upward movement toward the vibrating lever 38 by a counting pawl 170 pivotally mounted at 172 on a plate 174 clamped to the lower end of the lock bolt. The upper end of the pawl 170 is arranged to engage the end surface of the vibrating lever 38 when the treadle 44 is released. In the prior machine the lock bolt is delayed in its upward movement into the vibrating lever for at least one full rotation of the sewing shaft 34 so that one additional complete stitch is inserted before the present machine stops. Thus, with the counting pawl two stitches are inserted after the welt is severed and the treadle 44 is released. With the machine adjusted to insert stitches of normal length the distance between the severing position of the knife and the sewing point is less than two stitches, so that the final stitch is certain to cross the ends of the welt.

To insure that the pawl 170 will not release the lock bolt 40 before a second stitch has been inserted, the upper end of the pawl has a notch 176 arranged to be engaged by the lower rear corner of the vibrating lever 38 during the second vibration thereof. The pawl 170 is drawn forwardly against the vibrating lever by a spring 178 stretched between the pawl and a pin on a fixed part of the machine frame, so that the upper notched end of the pawl always engages the vibrating lever 38 before the lock bolt 40 does. During the first vibrating movement of the vibrating lever 38 after being engaged by the pawl, a spring 180 surrounding the lock bolt and acting between the upper end of the lock bolt and a counterbore in an opening which receives the lock bolt causes the pawl 170 to move upwardly until its upper end engages the underside of the vibrating lever. Rearward movement of the vibrating lever then enables the pawl to rise to the broken line position of Fig. 5 and a dog 182 moves behind a hooked extremity at the lower end of the pawl 170. During the next succeeding forward movement of the vibrating lever the pawl is entirely released from engagement with the under surface of the vibrating lever 38 so that the lock bolt 40 may enter the opening of the vibrating lever 38. The dog 182 is rotatably mounted on a pin 184 projecting from a block 186 clamped by a bolt 188 to a horizontal bar 190. The bar 190 is secured at its ends by screws 192 to the machine frame and has at its upper edge an eccentric pin 194 against which the dog 182 rests yieldingly. To maintain the dog in engagement with the eccentric pin 194 a rearwardly extending finger on the dog is connected to a tension spring 196 stretched between it and a fixed point on the machine frame. The arrangement is such that after the vibrating lever 38 engages the notch in the upper end of the pawl 170 and the pawl reaches the broken line position, the hooked lower extremity of the pawl moves into line with the forward end of the dog 182. The hooked extremity on the pawl then engages the dog 182 holding the pawl in the broken line position while the vibrating lever 38 moves forwardly, thus releasing

the pawl from the vibrating lever 38 and the lock bolt 40 moves upwardly. The lock bolt 40 then enters the opening in the vibrating lever and the machine is brought to rest after two stitches have been inserted, at least one of which stitches crosses the joint between the ends of the welt in a sewed seat shoe.

The nature and scope of the invention having been indicated and a particular embodiment having been described, what is claimed is:

1. A machine for manufacturing shoes with a welt attached throughout their marginal portions including their heel seats or, alternatively, with a welt attached about their foreparts only, said machine having stitch-forming feeding and guiding devices for the shoe parts, a welt severing knife mounted for movement toward and from the welt as it passes through the guiding devices, mechanism for actuating the knife, including a solenoid and an armature connected to the knife, a feeler for engaging the leading end of the welt already attached to a sewed heel seat shoe as that end approaches the stitch-forming devices, a main power line, a feeler actuated energizing switch for connecting the main line with the solenoid, a safety switch interposed in circuit with the feeler actuated switch to prevent unintentional operation of the welt severing knife, and driving and stopping mechanisms for the machine including a treadle, in combination with means including an operator-controlled solenoid energizing switch connected to the treadle for completing the circuit through the solenoid from the main line to cause the welt to be severed by the knife when sewing a shoe in which the welt is attached about the forepart only.

2. A machine for manufacturing shoes with a welt attached throughout their marginal portions including their heel seats or, alternatively, with a welt attached about their foreparts only, said machine having stitch-forming, feeding and guiding devices for the shoe parts, a welt severing knife mounted for movement toward and from the welt as it passes through the guiding devices, mechanism for actuating the knife, including a solenoid and an armature connected to the knife, a feeler for engaging the leading end of the welt already attached to a sewed heel seat shoe as that end approaches the stitch-forming devices, a main power line, a feeler actuated energizing switch for connecting the main line with the solenoid, a safety switch interposed in circuit with the feeler actuated switch to prevent unintentional operation of the welt severing knife and driving and stopping mechanisms for the machine including a treadle, in combination with means including an operator-controlled solenoid energizing switch connected to the treadle for completing the circuit through the solenoid from the main line to cause the welt to be severed by the knife when sewing a shoe in which the welt is attached about the forepart only, and a selector switch in circuit with the operator-controlled switch for rendering the operator-controlled switch effective to close the solenoid circuit or for disconnecting the operator-controlled switch from the solenoid when sewing a shoe in which the welt is attached throughout the marginal portions including the heel seat.

3. A machine for manufacturing shoes with a welt attached throughout their marginal portions including their heel seats, or, alternatively, with a welt attached about their foreparts only, said machine having stitch-forming, feeding and guiding devices for the shoe parts, a welt severing knife mounted for movement toward and from the welt as it passes through the guiding devices, mechanism for actuating the knife, including a solenoid and an armature connected to the knife, a feeler for engaging the leading end of the welt already attached to a sewed heel seat shoe as that end approaches the stitch-forming devices, a main power line, a feeler actuated energizing switch for connecting the main line with the solenoid and a safety switch interposed in cir-

cuit with the feeler actuated switch to prevent unintentional operation of the welt severing knife, in combination with means including an operator-controlled solenoid energizing switch for connecting the solenoid with the main line to cause the welt to be severed by the knife when sewing a shoe in which the welt is attached about the forepart only, and a selector switch in circuit with the operator controlled switch for rendering the operator-controlled switch effective or ineffective to close the solenoid circuit and to connect the safety switch in circuit with the solenoid when the operator-controlled switch is rendered ineffective.

4. A machine for manufacturing shoes with a welt attached throughout their marginal portions including their heel seats or, alternatively, with a welt attached about their foreparts only, said machine having stitch-forming, feeding and guiding devices for the shoe parts, a welt severing knife mounted for movement toward and from the welt as it passes through the guiding devices, mechanism for actuating the knife, including a solenoid and an armature connected to the knife, a feeler for engaging the leading end of the welt already attached to a sewed heel seat shoe as that end approaches the stitch-forming devices, a main power line, a feeler actuated energizing switch for connecting the main line with the solenoid and a safety switch interposed in circuit with the feeler actuated switch to prevent unintentional operation of the welt severing knife, in combination with means including a solenoid energizing switch for connecting the solenoid with the main line to cause the welt to be severed by the knife when sewing a shoe in which the welt is attached about the forepart only, means displaceable by the operator for actuating the safety switch in advance of the end of a seam to render one of the energizing switches effective to energize the solenoid, and a latch for retaining the safety switch in effective position.

5. A machine for manufacturing shoes with a welt attached throughout their marginal portions including their heel seats or, alternatively, with a welt attached about their foreparts only, said machine having stitch-forming, feeding and guiding devices for the shoe parts, a welt severing knife mounted for movement toward and from the welt as it passes through the guiding devices, mechanism for actuating the knife, including a solenoid and an armature connected to the knife, a feeler for engaging the leading end of the welt already attached to a sewed heel seat shoe as that end approaches the stitch-forming devices, a main power line, a feeler actuated energizing switch for connecting the main line with the solenoid and a safety switch interposed in circuit with the feeler actuated switch to prevent unintentional operation of the welt severing knife, in combination with means including an operator-controlled solenoid energizing switch for connecting the solenoid with the main line to cause the welt to be severed by the knife when sewing a shoe in which the welt is attached about the forepart only, means displaceable by the operator for actuating the safety switch in advance of the end of a seam to render one of the energizing switches effective to energize the solenoid, a latch for retaining the safety switch in activated position, and means for releasing the safety switch from the latch when the solenoid is energized.

6. A machine for manufacturing shoes with a welt attached throughout their marginal portions including their heel seats or, alternatively, with a welt attached about their foreparts only, said machine having stitch-forming, feeding and guiding devices for the shoe parts, a welt severing knife mounted for movement toward and from the welt as it passes through the guiding devices, mechanism for actuating the knife, including a solenoid and an armature connected to the knife, a feeler for engaging the leading end of the welt already attached to a sewed heel seat shoe as that end approaches the stitch-forming devices, a main power line, a feeler actuated

energizing switch for connecting the main line with the solenoid and a safety switch interposed in circuit with the feeler actuated switch to prevent unintentional operation of the welt severing knife, in combination with means including a solenoid energizing switch for connecting the solenoid with the main line to cause the welt to be severed by the knife when sewing a shoe in which the welt is attached about the forepart only, means displaceable by the operator for actuating the safety switch in advance of the end of a seam to render one of the energizing switches effective to energize the solenoid, a latch for retaining the safety switch in effective position, a treadle for controlling the operation of the machine, an arm connected to the treadle for actuating the solenoid energizing switch, and means actuated from the solenoid for releasing the safety switch from the latch.

7. A machine for manufacturing shoes with a welt attached throughout the marginal portions including their heel seats or, alternatively, with a welt attached about their foreparts only said machine having stitch-forming, feeding and guiding devices for the shoe parts, a welt-severing knife mounted for movement toward and from the welt as it passes through the guiding devices, mechanism for actuating the welt severing knife including a solenoid having an armature connected to the knife, a feeler for engaging the leading end of the welt already attached to a sewed heel seat shoe as that end approaches the stitch-forming devices, a main power line, a feeler actuated energizing switch for connecting the main line with the solenoid and a control treadle for starting the machine when depressed and for stopping it when released, in combination with means including an energizing switch for connecting the solenoid with the main line to cause the welt to be severed by the knife when sewing a shoe, in which the welt is attached about the forepart only, means for retaining the safety switch in circuit connecting position, and a treadle controlled by the operator and connected to actuate the operator controlled energizing switch when the treadle is released.

8. A machine for manufacturing shoes with a welt attached throughout their marginal portions including their heel seats or, alternatively, with a welt attached about their foreparts only, said machine having stitch-forming, feeding and guiding devices for the shoe parts, a welt severing knife mounted for movement toward and from the welt as it passes through the guiding devices, mechanism for actuating the welt severing knife including a solenoid having an armature connected to the knife, a feeler for engaging the leading end of the welt already attached to a sewed heel seat shoe as that end approaches the stitch-forming devices, a main power line, a feeler actuated energizing switch for connecting the main line with the solenoid and a control treadle for starting the machine when depressed and for stopping it when released, in combination with means including an energizing switch for connecting the solenoid with the main line to cause the welt to be severed by the knife when sewing a shoe, in which the welt is attached about the forepart only, means for retaining the safety switch in circuit connecting position, and a treadle controlled by the operator and connected to actuate the operator controlled energizing switch when the treadle is released.

toward and from a position where the solenoid energizing switch may be actuated when the control treadle is released, a connection between the arm on the operator displaceable lever and the control treadle for moving the arm into a position where the operator-controlled energizing switch is actuated when the control treadle is released, and a latch for retaining said arm in a position where the operator-controlled energizing switch may be actuated.

10. 9. A machine for manufacturing shoes with a welt attached throughout their marginal portions including their heel seats or, alternatively, with a welt attached about their foreparts only, said machine having stitch-forming, feeding and guiding devices for the shoe parts, a welt severing knife mounted for movement toward and from the welt as it passes through the guiding devices, mechanism for actuating the knife, including a solenoid and an armature connected to the knife, a feeler for engaging the leading end of the welt already attached to a sewed heel seat shoe as that end approaches the stitch-forming devices, a main power line, a feeler actuated energizing switch for connecting the main line with the solenoid and a safety switch interposed in circuit with the feeler actuated switch to prevent unintentional operation of the welt severing knife, in combination with means including a solenoid energizing switch for connecting the solenoid with the main line to cause the welt to be severed by the knife when sewing a shoe in which the welt is attached about the forepart only, means for retaining the safety switch in circuit connecting position, and a treadle controlled by the operator and connected to actuate the operator controlled energizing switch when the treadle is released.

15. 10. A machine for manufacturing shoes with a welt attached throughout their marginal portions including their heel seats or, alternatively, with a welt attached about their foreparts only, said machine having stitch-forming, feeding and guiding devices for the shoe parts, a welt severing knife mounted for movement toward and from the welt as it passes through the guiding devices, mechanism for actuating the knife, including a solenoid and an armature connected to the knife, a feeler for engaging the leading end of the welt already attached to a sewed heel seat shoe as that end approaches the stitch-forming devices, a main power line, a feeler actuated energizing switch for connecting the main line with the solenoid and a safety switch interposed in circuit with the feeler actuated switch to prevent unintentional operation of the welt severing knife, in combination with means including a solenoid energizing switch for connecting the solenoid with the main line to cause the welt to be severed by the knife when sewing a shoe in which the welt is attached about the forepart only, means for retaining the safety switch in circuit connecting position, and a treadle controlled by the operator and connected to actuate the operator controlled energizing switch when the treadle is released.

20. 11. A machine for manufacturing shoes with a welt attached throughout their marginal portions including their heel seats or, alternatively, with a welt attached about their foreparts only, said machine having stitch-forming, feeding and guiding devices for the shoe parts, a welt severing knife mounted for movement toward and from the welt as it passes through the guiding devices, mechanism for actuating the knife, including a solenoid and an armature connected to the knife, a feeler for engaging the leading end of the welt already attached to a sewed heel seat shoe as that end approaches the stitch-forming devices, a main power line, a feeler actuated energizing switch for connecting the main line with the solenoid and a safety switch interposed in circuit with the feeler actuated switch to prevent unintentional operation of the welt severing knife, in combination with means including a solenoid energizing switch for connecting the solenoid with the main line to cause the welt to be severed by the knife when sewing a shoe in which the welt is attached about the forepart only, means for retaining the safety switch in circuit connecting position, and a treadle controlled by the operator and connected to actuate the operator controlled energizing switch when the treadle is released, and means actuated by the solenoid armature for releasing the safety switch from its retaining means.
